HIS ATTORNEYS.

UNITED STATES PATENT OFFICE.

CHARLES DAVID BONSALL, OF PITTSBURGH, PENNSYLVANIA, ASSIGNOR TO P. H. MURPHY COMPANY, OF NEW KENSINGTON, PENNSYLVANIA, A CORPORATION OF PENNSYLVANIA.

CAR ROOF.

Application filed July 1, 1927. Serial No. 202,769.

My invention relates principally to improvement in metal car roofs of the all-steel flexible type wherein metal roof sheets extend from eaves to eaves of the car between carlines and are loosely connected along their adjacent margins by weather-proofing seam covers that are rigidly secured to said carlines and thus serve to hold roof sheets in position on the car.

10 The principal object of the present invention is to provide simple and efficient means for securing the seam covers to the carlines. Other objects are cheapness of construction and repair, fewness of parts 15 and ease of assembly. The invention consists of the parts and in the combinations and arrangement of parts hereinafter described and claimed.

In the accompanying drawing, which 20 forms part of this specification and wherein like numerals refer to like parts wherever they occur,

Fig. 1 is a vertical cross-section through the eaves portion of the car roof embodying 25 my invention, and

Fig. 2 is a cross-section through the seam on the line 2—2 in Fig. 1.

Referring to the accompanying drawing, my invention is shown in connection with a 30 car roof having roof substructure comprising wooden side plates 3 connected by metal carlines 4, preferably of substantially inverted T-shaped cross-section and are provided with depending end flanges 5 as shown in the drawings. Side sheathing boards 6 are secured to the outer face of each side plate and terminate below the upper edge thereof. The ends of the inverted T-shaped carlines are preferably seated in transverse 35 grooves 7 provided therefor in the tops of the side plates, and the outstanding base flanges and depending end flanges of said carlines are secured to said side plates by vertical and horizontal bolts 8 and 9, respectively. Eaves flashing strips 10 extend 40 longitudinally of the car at the eaves and are shaped and arranged to cover the upper end of the side sheathing and the upper corner of the side plates. As shown in the drawing the flashing is secured in place by the horizontal securing bolt 9 for the depending end flanges of the carlines.

Roof sheets 11 extend from eaves to eaves of the car between carlines with their end por-

tions movably supported on the tops of side 55 plates. The roof sheets are preferably provided with upwardly offset side marginal portions 12 that are inclined upwardly and terminate in upstanding side marginal seam flanges 13 that extend from end to end of 60 said sheets. The roof sheets are also provided at their eaves ends with depending flanges 14 which overhang the outer corners of the side plates and terminate in inturned portions that are normally spaced far enough 65 away from the side plates to permit the sheets to accommodate themselves to distortions of the car frame by sluing thereon.

Weatherproofing members in the form of inverted channel-shaped seam covers 15 70 straddle adjacent upstanding side marginal flanges 13 of the roof sheets and are provided at the lower edges of their side walls with outstanding base flanges 16 which rest flatwise on the sloping side marginal portions of adjacent sheets 12. The seam covers are of sufficient width to permit play of said flanges therebeneath, and the depth of said seam covers is sufficient to leave a space between the tops thereof and the tops of the 80 carlines. At their eaves ends, the seam caps 15 are provided with depending end flanges 17 which cover the space between the corners of adjacent sheets and terminate in inturned end portions which extend beneath the in-turned portions of the depending eaves flanges 14 of said sheets. The depending end flanges 17 of the seam covers 15 serve to limit outward sliding movement of the sheets and are normally spaced far enough 90 away from the depending eaves flanges of said sheets to permit play thereof.

The seam covers are rigidly secured to the carlines, preferably at a point adjacent to the eaves of the car by means of a double 95 or inverted U-shaped strap bolt 18. As shown in the drawing, the web of the strap bolt is permanently secured to the underside of the seam cover in direct contact therewith, preferably by means of a rivet 19, and the 100 branches of said bolt positioned one on each side of the upstanding web of the inverted T-shaped carline. The lower ends of the two branches of the double strap bolt terminate in cylindrical portions that extend 105 through openings or holes provided therefor in the lateral base flanges of the carline and are threaded to receive nuts 20. The strap

bolt is also provided with a nut lock comprising a perforated strip of metal 21, which is sleeved on the threaded ends of the depending branches of said strap bolt between the securing nuts 20 and the bottom of the carline and is provided with end projections or tabs 22 adapted to be sent down against the sides of the nuts.

The advantages of the above arrangement are its simplicity and cheapness of construction and fewness of parts and the ease with which the seam covers may be assembled on the car.

What I claim is:

- 15 1. A car roof comprising side plates connected by carlines and roof sheets spanning the car from side plate to side plate between carlines, seam covers connecting the adjacent marginal portions of said sheets, and means 20 for securing said seam covers in position, said means comprising strap bolts rigidly secured to said seam covers in direct contact therewith and removably engaging said carlines.
- 20 2. A car roof comprising side plates con-

nected by carlines and roof sheets spanning the car from side plate to side plate between carlines, seam covers loosely connecting the adjacent marginal portions of said sheets, and means for securing said seam covers in 30 position, said means comprising double strap bolts arranged with the webs thereof directly contacting with and rigidly secured to said seam covers and with the branches thereof removably engaging said carlines.

3. A car roof comprising side plates connected by carlines and roof sheets spanning the car from side plate to side plate between carlines, seam covers loosely connecting the adjacent marginal portions of said sheets, 40 and means for securing said seam covers in position, said means comprising inverted U-shaped strap bolts permanently secured to the seam covers with the webs of said bolts in direct contact with the underside of the 45 seam covers and with the branches of said bolts removably engaging said carlines.

Signed at New Kensington, Pa., this 27th day of June, 1927.

CHARLES DAVID BONSALL.
